PROCESS FOR HYDROCARBON OIL
CONVERSION

Carbon P. Dubbs, Wilmette, Ill., assignor, by
mesne assignments, to Universal Oil Products
Company, Chicago, Ill., a corporation of Dela-
ware

Application January 17, 1927, Serial No. 161,483

11 Claims. (Cl. 196—62)

The invention relates to a conversion of hydrocarbon oils under heat and pressure in the presence of a hydrogenating gas, such as hydrogen, for the purpose of making larger quantities of lighter hydrocarbons containing high percentages of saturated hydrocarbons.

I am aware that the treatment of hydrocarbon oils with hydrogen or the like has been the subject of considerable development in the prior art, but the processes heretofore used had a relatively low efficiency and produced only relatively small amounts of the desired products.

One of the objects of this invention is to improve the efficiency of the process of the treatment by subjecting the hydrocarbon oils to a repeated treatment until the desired products are obtained in the quantity desired while at the same time the operation of the process is kept within efficient and economical limits by subjecting the hydrocarbon oils during each pass of the treatment to a relatively mild action by the hydrogenating agent.

In short, the process consists in passing hydrocarbon oil through a treating zone where it is heated to conversion temperature under any pressure desired, then causing separation of the heated oil into vapors and heavy hydrocarbon constituents while the vapors are subjected to further separation into light products and heavier condensates, the condensate comprising all the fractions which have not been sufficiently treated to give the desired product. The light vapors are then condensed and collected as a final product while the insufficiently treated condensates are returned to the heating zone for further treatment.

One of the features of the invention is the injection of a hydrogenating agent, such as hydrogen, into the material undergoing conversion at any step of the process which will produce the desired results. A further feature of the invention is to inject said agent or hydrogen preferably into the hydrocarbons which will be subjected to a repeated treatment through the conversion zone, and which will be kept in circulation therethrough until their transformation into the desired product. This injection can furthermore be effected into the hydrocarbons undergoing treatment either before or after their passage through the heating zone, according to the degree of conversion desired.

It is readily seen that there are unlimited numbers of methods to carry out the object of this invention, and I do not wish to limit myself to any one particular apparatus or method.

An apparatus to carry out this invention can be conceived without difficulty by those skilled in the art, and any apparatus by which the object of the invention can be carried out is well within the scope of the invention, and I will illustrate hereinafter a particular method and apparatus in which this invention can be carried out without limiting myself to this particular design.

In the drawing the single figure is a side elevational view showing schematically and diagrammatically a suitable form of apparatus.

Referring to the drawing, oil can be pumped from any suitable source, not shown, through line 1 and passed through pump 2, line 3 and line 4 controlled by a valve 5 into the upper portion 5 of a dephlegmator 6. The dephlegmator can be of any suitable design. In the dephlegmator the oil is preheated to some extent by the vapors undergoing fractionation therein, and said oil and reflux condensate are withdrawn from the bottom of the dephlegmator 7 controlled by valve 8 and passed by means of pump 9 controlled by valves 10 into main feed line 11. The oil from line 11 is directed through heating tubes 12 positioned in furnace 13 which can be of any suitable design and heated in any suitable manner, not shown. If desired a portion of the oil can be passed from line 3 directly into line 7 to be directed into heating zones 12 without passing through dephlegmator 6. This is effected by controlling the opening of valve 5 within line 4 and of valve 14 on line 15.

The oil is heated in heating coils 12 to proper temperatures of conversion and passed therefrom through transfer line 16 controlled by valve 17 into reaction chamber 18. According to conditions of the operation in the reaction chamber vaporization may or may not take place, although some gas may evolve therein. The products of reaction can be withdrawn from the reaction chamber from any desired place, i. e., as shown in the drawing, from the bottom through line 19 controlled by valve 20 or by the side line 21 controlled by valve 22. These two lines merge into line 23 controlled by valve 24 and pass the products of reaction into vapor separating chamber 25. The gas or vapors separated in reaction chamber 18 may pass from the top thereof through line 26 controlled by valve 27 into line 28 controlled by valve 29 directly 45 through which they are directed to vapor separating chamber 25 with products of reaction withdrawn from their places of reaction chamber 18, or these gases and vapors can be directed 50 through line 28 controlled by valve 29 directly 55

into the dephlegmator 6 without passing through vapor separating chamber 25.

Suitable baffle means may be used to alter the passage of vapors and to increase the time element of the reaction. In said vapor separating chamber 25 the products of reaction entering through line 23 are separated into heavy liquid portions which accumulate at the bottom thereof and into vapors which are withdrawn from the top of chamber 25 through line 30 controlled by valve 31 which merges with line 28 to direct the vapors from chamber 25 into the dephlegmator 6. The heavy liquid products of reaction accumulated in the bottom of chamber 25 are drawn off from the bottom or side thereof through lines 32 controlled by valves 33 and evacuated from the process through line 34 controlled by valve 35. In the dephlegmator 6 the vapors are subjected to fractionation and by controlling the temperature at the top of the dephlegmator the suitably desired products are drawn off from the top thereof in the form of vapors through line 36 controlled by valve 37 and pass into condensing means, shown at 38, from where the liquid condensates and gases are directed into collecting means 39. Collecting means 39 is provided with a gas release line 40 controlled by valve 41 and liquid draw off 42 controlled by valve 43. If the amount of raw oil fed into the top of dephlegmator 6 through line 4 is insufficient to produce the desired amount of cooling additional cooling can be effected by reserving a portion of the condensate accumulated in collecting means 39 through line 44 controlled by valve 45 and pump 46 in line 47.

As a feature of the invention a hydrogenating gas, such as hydrogen, gaseous hydrogenated compounds can be introduced into the oil undergoing treatment at any desired step of the treatment according to the degree of conversion and characteristics of product desired. For instance, hydrogen or the other agents can be withdrawn from any suitable source, not shown, through line 48 and passed by means of pump 49 into line 50 controlled by valve 51 and into distributing header 52. From header 52 there are several distributing lines which are connected with various parts of the process, such as line 53 controlled by valve 54 which connects with the discharge of the raw oil pump 2, also line 55 controlled by valve 56 which connects with the feed line 11 at the inlet of the heating tubes 12. Also line 57 controlled by valve 58 which connects the hydrogen or other agent header 52 with the transfer line 16 from which the hot oil is discharged through the heating coil 12. Or a line 59 controlled by valve 60 connects the header 52 with the line 19, and by using this line hydrogen or the other agents used can be injected into the products of reaction drawn off from chamber 18.

It can be seen that by controlling the opening of the various valves 54, 56, 58 and 60 and utilizing either one or the other or several of the valves, hydrogen can be introduced in varying proportions at any one or more of the points heretofore described. These connections permit introduction of hydrogen into the liquid hydrocarbons passing rapidly through the system before or after they have received the heat of conversion.

It may be desirable to accomplish the reaction by means of the hydrogen or of any other agent injected in the system into the products of reaction while they are in the vapor form. To this object I have shown a supply line 61 passing into

pump 62 through which hydrogen can be injected in the vapors of the process at various points thereof, i. e. by opening valve 63 on line 64 the reacting agent can be injected in the vapors formed in reaction chamber 18 and passing on line 66 the other reacting agent can be injected into vapors leaving vapor separating chamber 25 before they are introduced into dephlegmator 6, or by opening valve 67 on line 68 connected to the discharge pump 62 the reacting agent can be introduced into vapors forming the final product of the system.

It is well understood that I have shown a number of ways in which and steps of the process at which the reacting agent can be introduced. There are a number of other desirable places in which the reacting agent can be injected, i. e. in the reflux leaving the dephlegmator.

As a further object of the invention, it may be desirable to control the temperature of the reacting agent introduced in the system at various places, as heretofore described. For this purpose any suitable means for heating the gas can be used, and I have indicated a preheater at 68 connected to the discharge line 50 from pump 49 and controlled by valves 69 and 70.

The temperatures and pressures which can be used in the system cover a wide range according to the purpose of the operation, i. e. the material undergoing conversion can be heated in heating coil 12 at temperatures varying from 500 to 1500° F., more or less. One of the factors entering into the control choice of the temperature at which the conversion is effected is the step of the process at which the reacting agent is to be introduced. In other words, it may be desirable to subject hydrocarbon oil undergoing conversion to a higher temperature if the gaseous agent is introduced into the process after the hydrocarbon oils have been heated, or to a lower temperature if these reducing agents are introduced in the oil before it is passed through the heating coil.

The pressure must be regulated according to the material treated and product desired, and the pressures used may differ widely in the treatment of two different kinds of hydrocarbons. It will also depend upon the reacting agent used. For instance, a pressure of 3000 lbs. may be sufficient in one case, while in another operation it may be necessary to use pressure as high as 5000 lbs. or more. Pressures of this high order are to be distinguished from those customarily employed in cracking since at the temperatures above set forth and in the presence of hydrogen, they result in substantial hydrogenation of the oil for the production of larger quantities of lighter oils containing high percentages of saturated hydrocarbons. Also under these high pressures, the conversion reactions take place while a substantial part of the oil is in the liquid phase, the effect being a conjoint cracking and hydrogenation of the oil. By the term "destructive hydrogenation" employed in the claims I intend to refer to this conjoint cracking and hydrogenation of the oil. It is understood, however, that the higher the pressure the speedier the reaction, and that if the desired results can be obtained from the particular material used by operating under a number of different pressures at a range of pressures, it would be preferable to operate under the higher pressure producing said results.

It is well understood that the proportion of the reacting agent such as introduced in the system

will vary, and that no figure can be accurately determined without considering together the materials treated, the products and temperature and pressure conditions with which the process is to be carried out.

In carrying out the process, I have shown in the apparatus and method illustrated above, a method for separating the sufficiently treated hydrocarbons from the insufficiently treated hydrocarbons by means of dephlegmation or fractional condensation. That is to say that the various constituents of the vapors produced would be separated according to their boiling points. On account of the complexity of the products made in my process, it may be that several of the materials made which are to be withdrawn as final products have approximately the same boiling points so that their separation in this manner is nearly impossible. My invention contemplates the use of any other separating method, such as filtering or separation by means of chemical reagents, from which the insufficiently treated material can be further recovered by decantation or precipitation.

25 I claim as my invention:

1. A process for the destructive hydrogenation of hydrocarbon oil which comprises passing the oil in admixture with a hydrogen-containing gas through a restricted heating coil and heating the same therein to a conversion temperature under a superatmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, the pressures employed being substantially in excess of 1000 lbs. per square inch, separating the oil into vapors and non-vaporous constituents, and condensing said vapors.

2. A process for the destructive hydrogenation of hydrocarbon oil which comprises passing the oil in admixture with a hydrogen-containing gas through a restricted heating coil and heating the same therein to a conversion temperature under a superatmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, introducing additional hydrogen-containing gas into the oil in said reaction zone, separating the oil into vapors and non-vaporous constituents, and condensing said vapors.

3. A process for the destructive hydrogenation of hydrocarbon oil which comprises passing the oil in admixture with a hydrogen-containing gas through a restricted heating coil and heating the same therein to a conversion temperature under a super-atmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, the pressures employed being substantially in excess of 1000 lbs. per square inch, separating the oil into vapors and non-vaporous constituents, dephlegmating the vapors, returning insufficiently converted constituents to said heating coil and thence to said reaction zone for

further treatment under conversion and hydrogenating conditions therein and condensing the dephlegmated vapors.

4. A process for the destructive hydrogenation of hydrocarbon oil which comprises passing the oil in admixture with a hydrogen-containing gas through a restricted heating coil and heating the same therein to a conversion temperature under a super-atmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, introducing additional hydrogen-containing gas into the oil in said reaction zone, separating the oil into vapors and non-vaporous constituents, dephlegmating the vapors, returning insufficiently converted constituents to said heating coil and thence to said reaction zone for further treatment under conversion and hydrogenating conditions therein, and condensing the dephlegmated vapors.

5. A process for the destructive hydrogenation of hydrocarbon oil which comprises passing the oil in admixture with a hydrogen-containing gas through a restricted heating coil and heating the same therein to a conversion temperature under a super-atmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, withdrawing vaporous reaction products from said reaction zone and introducing the same to a secondary reaction zone, mingling said vaporous products with further quantities of hydrogen-containing gas in said secondary reaction zone, and removing and condensing vapors from said secondary reaction zone.

6. A process for the treatment of hydrocarbon oil for the production of lighter hydrocarbons containing high percentages of saturates which comprises passing the oil in admixture with a hydrogen-containing gas through a restricted heating coil and heating the same therein to a conversion temperature under a super-atmospheric pressure sufficient to effect hydrogenation and conversion at the temperature to which the oil is raised, discharging the hot oil and gas into an enlarged reaction zone maintained at conversion temperature and under sufficient pressure to effect hydrogenation and conversion therein, introducing additional hydrogen-containing gas into the oil in said reaction zone, withdrawing vaporous reaction products from said reaction zone and introducing the same to a secondary reaction zone, mingling said vaporous products with further quantities of hydrogen-containing gas in said secondary reaction zone, and removing and condensing vapors from said secondary reaction zone.

7. A process for the destructive hydrogenation of hydrocarbon oil which comprises heating a flowing stream of the oil to conversion temperature under a pressure sufficient to maintain substantial portions of the oil in liquid condition, discharging the hot oil stream into an enlarged reaction zone maintained under temperature and pressure conditions adequate to effect liquid phase conversion and hydrogenation therein, introducing sufficient hydrogen-containing gas di-

- rectly into the liquid oil in said reaction zone to effect hydrogenation thereof, removing vaporous reaction products from said zone and introducing the same to a secondary reaction zone, 5
5 mingling the vaporous reaction products in said secondary zone with additional quantities of hydrogen-containing gas to effect further hydrogenation thereof, withdrawing vapors from said secondary zone and subjecting the same to condensation. 10
10 8. A process for the destructive hydrogenation of hydrocarbon oil which comprises passing the oil in admixture with a hydrogen-containing gas through a restricted heating coil and heating the same therein to a conversion temperature under a super-atmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, the pressures employed being at least in the neighborhood of about 3000 pounds per square inch, separating the oil into vapors and non-vaporous constituents, dephlegmating the vapors, 15
15 returning insufficiently converted constituents to said heating coil and thence to said reaction zone for further treatment under conversion and hydrogenating conditions therein and condensing the dephlegmated vapors. 20
20 9. A process for the destructive hydrogenation reaction zone maintained at conversion temperature and under sufficient pressure to effect hydrogenation and liquid phase conversion therein, the pressures employed being at least in the neighborhood of about 3000 pounds per square inch, separating the oil into vapors and non-vaporous constituents, and condensing said vapors. 25
25

9. A process for the destructive hydrogenation

of hydrocarbon oil which comprises passing the oil in admixture with a hydrogen-containing gas through a restricted heating coil and heating the same therein to a conversion temperature under a super-atmospheric pressure sufficient to effect hydrogenation and liquid phase conversion at the temperature to which the oil is raised, discharging the hot oil and gas into an enlarged reaction zone maintained at conversion temperature and under sufficient pressure to effect hydrogenation and liquid phase conversion therein, the pressures employed being at least in the neighborhood of about 3000 pounds per square inch, separating the oil into vapors and non-vaporous constituents, dephlegmating the vapors, 15
15 returning insufficiently converted constituents to said heating coil and thence to said reaction zone for further treatment under conversion and hydrogenating conditions therein and condensing the dephlegmated vapors. 20

10. The process as defined in claim 2 further characterized in that pressures at least of the order of about 3000 pounds per square inch are employed.

11. The process as defined in claim 4 further characterized in that pressures of 3000 pounds per square inch and above are employed.

CARBON P. DUBBS.
